UNITED STATES PATENT OFFICE.

EMRY KISS, OF LORAIN, OHIO.

TOOL FOR TWISTING WAX-ENDS.

SPECIFICATION forming part of Letters Patent No. 715,086, dated December 2, 1902.

Application filed March 7, 1902. Serial No. 97,067. (No model.

To all whom it may concern:

Be it known that I, EMRY KISS, a citizen of the United States, residing at Lorain, in the county of Lorain and State of Ohio, have 5 invented certain new and useful Improvements in Tools for Twisting Wax-Ends; and I do hereby declare the following to be a full, clear, and exact description of the invention, such as will enable others skilled in the art 10 to which it appertains to make and use the same.

This invention relates to certain new and useful improvements in shoemakers' tools for twisting wax-ends, and has for its object to 15 construct a device particularly adapted for use by shoemakers in making what are known in the trade as "wax-ends."

Briefly described, the invention consists of a pear-shaped body having a tapering handle 20 extending from its smaller end and a hook secured in its larger end. The thread from which the wax-ends are formed is connected onto this hook, and one end of the doubled thread is held in the hand of the operator, 25 while the handle or stem connected to the pear-shaped body is rolled on the limb of the operator to twist the threads together prior to and during the waxing process.

In describing the invention in detail reference will be had to the accompanying drawings, forming a part of this specification, and wherein like numerals of reference will be employed to indicate like parts throughout the different views, in which—

35 Figure 1 is an illustrative view showing the manner of using my improved device. Fig. 2 is a detail plan view of the device.

The device consists of a pear-shaped body 1, from the smaller end of which projects a 40 handle or stem 2, that tapers throughout its length toward the free end. Connected to the larger end of the pear-shaped body 1 in any suitable manner and in line with the handle or stem 2 is a hook 3, with which the 45 thread 4 is engaged, the other end of the thread or strands of thread being adapted to be held in the hand of the operator, as fully illustrated in Fig. 1 of the drawings.

In the making of wax-ends the thread from 50 which they are made is doubled, and the con-

nected ends of the strands are looped over the hook 3. The other ends of the strands of the thread are held in the hand of the operator, and the stem or handle 2 is placed on the leg and rolled backward and forward by the hand 55 of the operator, so as to twist the strands of the thread together. The wax is generally applied to the twisted strands by the hand employed for rolling the stem to twist the threads, as it will be observed that the operator may readily hold the device while using the one hand for waxing. To this end the stem 2 may be inserted between and held by the legs of the operator, or when merely laid in the lap of the operator the weight of the 60 device prevents the untwisting of the threads as long as they are held taut.

In the practice of the invention it will be observed that various changes may be made in the details of construction without departing from the general spirit of the invention.

Having fully described my invention, what I claim as new, and desire to secure by Letters Patent, is—

1. In a device of the character described, a 75 pear-shaped body having a handle or stem connected to one end, and a hook to the other end, substantially as described.

2. In a device of the character described, a pear-shaped body having a tapering handle 80 connected to one end, and means connected to the opposite end for holding a thread, substantially as described.

3. In a device of the character described, a pear-shaped body having a tapering handle 85 or stem connected to its smaller end, and means connected to the larger end for holding a thread, substantially as described.

4. In a device of the character described, a pear-shaped body having a tapering handle 90 or stem connected to its smaller end, and a hook connected to its larger end in line with the tapering handle or stem, substantially as described.

In testimony whereof I affix my signature 95 in presence of two witnesses.

EMRY KISS.
